UNITED STATES PATENT OFFICE.

ROBERT M. KEATING, OF SPRINGFIELD, MASSACHUSETTS, ASSIGNOR TO THE
R. M. KEATING MOTOR COMPANY, OF PORTLAND, MAINE, A CORPORA-
TION OF MAINE.

BACK-PEDALING BRAKE.

SPECIFICATION forming part of Letters Patent No. 691,147, dated January 14, 1902.

Application filed September 13, 1897. Serial No. 651,450. (No model.)

To all whom it may concern:

Be it known that I, ROBERT M. KEATING, a citizen of the United States of America, residing in Springfield, in the county of Hampden 5 and State of Massachusetts, have invented new and useful Improvements in Back-Pedal Brake Mechanism, of which the following is a specification, reference being had to the accompanying drawings and letters of reference 10 marked thereon.

In the drawings, like letters of reference indicating like parts, Figure 1 is an isometric perspective of one end of a wheel-hub. Fig. 2 is a like view of an eccentric split ring to 15 be mounted thereon. Fig. 3 is a side view of the sprocket-wheel. Fig. 4 is an isometric perspective of a shell adapted to set over the end of the hub. Fig. 5 is a sectional view of the same. Fig. 6 is an end view of the hub 20 and brake mechanism in section, the sprocket-wheel being shown in full lines mounted thereon, it being located back of the plane on which the section is taken. Fig. 7 is an end view of the hub. Fig. 8 is an end view of 25 the hub with the brake-ring mounted thereon, the ring being located in a position to allow the free revolution of the hub; and Fig. 9 is a like view of the hub with the brake-ring mounted thereon, the ring being in position 30 to produce the necessary binding or frictional effect and to restrain the revolution of the hub.

In detail, *a* indicates the hub; *b*, eccentric-shaped end portion thereof; *c*, an elevation or 35 raised part concentric with the axial line of the hub; *d*, a shoulder; *e*, an eccentric split ring; *f*, a lateral lug on the same; *g*, a sprocket-wheel; *h*, a recess therein; *i*, a cap; *j*, annular flange, and *k* lateral projections.

The construction and operation of my device 40 are as follows: The sprocket-wheel is of course mounted upon the hub and revolves with it. The means of locking the hub and sprocket-wheel, however, together differs 45 materially from that heretofore employed in that instead of the sprocket-wheel being attached directly to the hub it is mounted upon the part *c* of the hub and is restrained from rotating thereon by reason of its engagement 50 with the lug *f*, projecting laterally from the eccentric split ring *e*, which lug enters the

recess *h* in the sprocket-wheel, so that the sprocket-wheel is free to revolve upon the hub to the extent permitted by the movement of the ring *e* upon the hub, and the movement 55 of the ring *e* upon the hub is limited by the walls *l* and *m* of the recess between them. The portion *c* of the hub is concentric with its axial line, and the sprocket-wheel is mounted thereon. The portion *b* of the hub upon 60 which the split ring is mounted is eccentric with the axial line of the hub, and the split ring is eccentric also, but in reverse direction to the surface *b*, so that when the split ring is in position, as shown in Figs. 6 and 8, 65 the exterior surface of the split ring is substantially a true circle, except as to the portion cut therefrom, and is of a diameter to just fit within and clear the inner wall of the flange of the cap *i*. When, however, the split 70 ring is moved to the position shown in Fig. 9, it is expanded by reason of its riding upon the eccentric surface upon which it is mounted, and thus the outer surface or periphery of the split ring is forced against 75 the inner wall of the flange *j* of the cap *i* and friction thereby produced between the periphery of the split ring and the inner wall of said flange, thus checking the rotation of the hub and operating as a brake. 80 The cap *i* is of course restrained from rotation, and by preference this is produced by providing it with projecting parts *k*, which are suitably fastened to the frame. It will now be seen that if the brake mechanism be 85 set and the sprocket-wheel rotated in the direction indicated by the arrow *o* it will by reason of its engagement with the lug *f* first move the split ring to the position indicated in Figs. 6 and 8, or, in other words, move it 90 to a position where it contracts to its smallest diameter, thus releasing it from frictional engagement with the cap-flange and permitting free rotation of the sprocket-wheel. When, however, back-pedaling is commenced, thus 95 rotating the sprocket-wheel in the opposite direction, it results in first moving the split ring in a direction which will cause it to expand and bear with its periphery against the inner wall of the annular flange *f*, thus applying the requisite friction to effectually prevent rotation of the wheel. It will also be 100

seen that the extent of friction or brake action applied may be readily regulated by the rider by a movement of the pedals in the requisite direction, so as to set the brake-ring in 5 the desired position.

Having, therefore, described my invention, what I claim, and desire to secure by Letters Patent, is—

1. The combination of a hub provided with 10 an eccentric exterior portion and a concentric portion, a sprocket-wheel mounted on said concentric portion, an eccentric split ring mounted in reverse direction on said eccentric portion and arranged to engage the 15 sprocket-wheel, and a surface adapted to be engaged by said ring when expanded, substantially as set forth.

2. The combination of the hub *a* having eccentric circumferential portion *b*, and concentric circumferential portion *c*, and recess 20 between the walls *l* and *m*; a sprocket-wheel having a recess *h*, mounted upon the concentric circumferential portion *c*, eccentric split ring *e* having a lug *f* and mounted upon the 25 eccentric circumferential portion *b* with the

lug resting in said recess, and a cap *i*, having flange *j* arranged with the flange closely adjacent to the circumference of the split ring, substantially as shown.

3. In a brake mechanism, a rotating part 30 provided with an eccentric circumferential surface, an eccentric split ring mounted in reverse direction thereon, a fixed surface for the ring to bear against when expanded, and means to rotate said ring on the eccentric 35 surface whereby the same is expanded, substantially as set forth.

4. In a brake mechanism, the combination of a hub, a ring mounted thereon, an inclined surface between the ring and hub adapted to 40 cause the former to expand when moved in one direction, a fixed friction-surface for the ring to bear against, and positive means to cause movement between the movable parts, substantially as set forth.

ROBERT M. KEATING.
